UNITED STATES PATENT OFFICE.

ARTHUR C. JACKSON, OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

LOCK.

1,130,822.

Specification of Letters Patent.

Patented Mar. 9, 1915.

Application filed January 29, 1914. Serial No. 815,135.

To all whom it may concern:

Be it known that I, ARTHUR C. JACKSON, a citizen of the United States, residing at Philadelphia, county of Philadelphia, and State of Pennsylvania, have invented a new and useful Improvement in Locks, of which the following is a full, clear, and exact description, reference being had to the accompanying drawings, which form a part of this specification.

A freezing of the tumblers one with the other often occurs with tumbler locks. This occurs, for instance, in cold weather particularly. I have devised a construction whereby this may be avoided. Speaking generally, I accomplish the result as follows: Between contiguous tumblers, near their outer end, which engages or interlocks with tumbler stump dog or bolt, whichever 10 the case may be, I interpose a wire, or plate, or other like device, which acts as a separator, and at the pivotal portion of the tumblers I insert between contiguous tumblers, a wire ring or washer. In general, I 15 use two uprights or lugs, which may be grooved, between which are stretched or inserted wires or plates, which lie between successive tumblers. These uprights are mounted on the lock casing or on the plate or bolt 20 to which is also mounted the pivot or tumbler stud, upon which the tumblers pivot or swing. The tumblers are assembled one after the other upon this plate, and between each pair of tumblers a wire or plate is 25 placed between the uprights and lies between said tumblers. A wire ring or washer is interposed between each tumbler surrounding 30 the pivotal pin.

I will now describe the embodiment of my 35 invention, as shown in the accompanying drawings.

Figure 1 is a front view of a lock embodying my improvement with a portion of the face removed. Fig. 2 is a section between the tumblers at right angles to the lines 3—3, 40 Fig. 1. Fig. 3 is a section on the line 3—3, Fig. 1. Fig. 4 is a detail perspective view of the plate or bolt.

In the embodiment of my invention, as de-

scribed in the drawings, I have shown the same as applied to a shackle lock, although the invention is not limited to any particular lock.

In the drawings, *a* is the shackle, *b* the dog, *c* the bolt, *d*, *d*, *d*, etc., are the tumblers as shown. Projecting vertically from the bolt *c* are the lugs *e*.

i is the opening for the pivotal pin *f* on which the tumblers and bolt are pivoted.

The tumblers are provided with apertures 60 so that they can be mounted on the pivotal pin *f*. Between each pair of tumblers, and surrounding the pivotal pin *f*, is interposed the wire separator or washer *g*.

h are wires extending from one lug to the other lug, and lying between each pair of tumblers. By this construction, all danger of the tumblers freezing or attaching one to the other is avoided.

Having now fully described my invention, 70 what I claim and desire to protect by Letters Patent is—

1. In a lock, the combination with a plurality of tumblers, of a plate, vertical lugs projecting from said plate, and wires passing 75 between said lugs and lying between contiguous tumblers.

2. In a lock, the combination with a plurality of tumblers, of vertical lugs extending transversely of the direction of extension of 80 the tumblers, means independent of the tumblers to support the lugs, and spacing devices extending between said lugs and lying between contiguous tumblers.

3. In a lock, the combination of a plurality of tumblers, a pivot pin upon which said tumblers are mounted, spacers surrounding said pin and extending between contiguous tumblers, said spacers being separate and independent from each other and 90 held in operative position by said pin, and spacing devices lying between contiguous tumblers at a point removed from the pivotal point.

4. In a lock, the combination of a plurality of tumblers, a pivot pin upon which said tumblers are mounted, spacers surrounding said pin and between contiguous 95

tumblers, vertical lugs extending transversely of the direction of extension of the tumblers, and spacing devices extending between said lugs and lying between contiguous tumblers.

5. In a lock, the combination with a plurality of tumblers and a plate, of a pivot pin upon which said tumblers and plate are pivotally mounted, spacing devices extend-

ing between contiguous tumblers, and means 10 on the plate to support said spacing devices.

In testimony of which invention, I have hereunto set my hand, at Philadelphia, on this 26th day of January, 1914.

ARTHUR C. JACKSON.
